(57) **CLAIM**

The ornamental design for a hook receiver, as shown and described.

DESCRIPTION

FIG. 1 is a top, front, right side perspective view of a hook receiver.

FIG. 2 is a front elevation view thereof.

FIG. 3 is a left side elevation view thereof.

FIG. 4 is a right side elevation view thereof.

FIG. 5 is a rear elevation view thereof.

FIG. 6 is a top plan view thereof.

FIG. 7 is a bottom plan view thereof.

FIG. 8 is a cross section view thereof taken along line 8-8 of FIG. 2; and,

FIG. 9 is a top, front, right side perspective view thereof, shown in an environment of use.

The evenly spaced broken lines in the drawings depict portions of the hook receiver that form no part of claimed design. The additional evenly spaced broken lines shown in FIG. 9 are for the purposes of illustrating environment only and form no part thereof. The dash-dot-dot-dash broken lines shown in FIGS. 1, 2, 5, 6 and 9 represent the boundary of the claim and forms no part thereof.
